REFERENCE BOOK CABINET

Thomas H. Lyons, Union City, Ind., assignor to
 Lyons-Mee, Incorporated, Union City, Ind., a
 corporation of Indiana

Application January 26, 1948, Serial No. 4,312

2 Claims. (Cl. 312—34)

1

The present invention relates to furniture and more particularly to a cabinet for containing a plurality of large reference books which are kept normally retracted or enclosed in the cabinet but are maintained readily available for withdrawal to a position where they can be opened and supported in open position.

While the structure is adapted to numerous uses, it is particularly and especially designed for use in industrial establishments, such for example as automobile repair shops and automobile parts sales offices. In such establishments it is necessary to maintain a large stock of different mechanical parts, all of which are kept sorted in storage bins and all of which are indexed in loose leaf catalogues which identify the parts, state their storage locations, prices, uses, etc.

In the operation of such a business it is necessary to make constant reference to such catalogues or books. Considerable difficulty has been experienced heretofore by mechanics, storekeepers and others in keeping such books neat and in good condition and readily accessible.

A primary object of the present invention is to provide an article of furniture which will serve simultaneously as a counter or table on which business may be transacted, bills and orders written, etc., and as a cabinet for housing books or catalogues and for rendering them quickly accessible for use.

Other objects and advantages of the invention will appear from the following description of a preferred embodiment which has been used successfully in actual practice and which is therefore at present preferred as constituting the best embodiment of the invention.

This preferred embodiment is illustrated in the accompanying drawings which form part of this application for Letters Patent, in which

Figure 1 is a perspective view, partly broken away, showing a cabinet constructed in accordance with the principles of the invention, housing a plurality of books, certain of which are shown hung in retracted position and one of which is shown in opened position;

Fig. 2 is a detail cross-sectional view taken transversely through an upper portion of the cabinet;

Fig. 3 is a detail perspective view showing one of the pivoted panels with a book binding attached; and

Fig. 4 is a detail longitudinal sectional view taken through the upper portion of the cabinet showing books hung in retracted position.

Generally speaking, the structure contem- 55

2

plated by the invention comprises a cabinet, made of wood, metal or the like, having in its upper portion a table or counter surface disposed at appropriate height and formed in part at least of a plurality of panel elements which are mounted for swinging about a horizontal axis. These elements have book bindings secured to them, and the book pages are secured in the bindings so as normally to hang in compartments provided in the upper portion of the cabinet. The panels are rotatable individually to swing the depending books from within the compartments to rest on the top surface of the cabinet, where they may be opened and their leaves turned in the usual manner.

Such a structure is shown in the accompanying drawings. Referring first to Fig. 1, the cabinet comprises a pair of vertical end walls 1 connected by a front wall 1a, a lower rear wall 2, and a front top wall or cover 3. All these walls, and the other parts hereinafter to be described, may be made of wood, metal or the like in the manner of any standard article of commercial or office furniture.

The lower portion of the cabinet, which forms no part of the present invention, may include a storage space 4, best shown in Fig. 4, behind the lower rear wall 2. This wall may be made in one piece and hinged for opening, or it may be vertically divided to provide in effect a number of doors or closures which may be opened to provide access to different parts of the space 4. This space is covered by a top 5 which forms the roof of the storage space 4 and the floor of the book compartments which will now be described.

These book compartments, each of which is designated 6, are defined by vertical partitions 7 which extend from the floor 5 to the level of the top wall 3 of the cabinet. The compartments are all open at their backs, as shown in Fig. 1, and thus constitute stalls each of which is properly proportioned as to height, width and depth to contain a reference book 8.

The series of partitions 7 may extend across the whole width of the cabinet, and the cabinet is preferably about twice as deep (front to rear dimension) as each of the books is high. The front half of the cabinet has filler blocks or panels 9 permanently secured between the forward parts of the partitions 7, so as to form therewith the fixed top 3, which serves as the front portion of a counter or table surface. The rear half of the cabinet top is formed by a series of panels 10 disposed between the rear parts of the parti-

tions 7, and each of these panels is independently journaled for rotation on a long fixed shaft or rod 11 which is mounted in the two end walls 1 and passes successively through holes 12 in the panels 10 and through similar holes 13 (Fig. 4) in the partitions 7. Thus the rod or shaft 11 is securely supported, and the panels 10 are journaled for rotation on the rod.

The forward edge of each of the panels 10 and the rear edge of each of the fixed filler blocks 9 are complementally offset or rabbeted to provide a stepped joint, as shown at 14, so that the offset provides an abutment for the swinging panel 10 limiting its rotation and holding it flush in the plane of the surface 3. However, the panel is free to be turned by lifting its rear edge 15, which will cause its offset forward edge to swing down into the compartment through approximately 180° until the rear edge 15 engages the top of the rear edge of the adjacent filler block 9, as is indicated in Fig. 2 and as is shown in the case of the third panel from the left in Fig. 1.

Each book 8 includes any suitable type of binding 16, the back of which is secured, as by screws 17, to the normally under side of one of the panels 10. The back may be made of metal or equivalent material and have hinged to it a pair of side covers, with cross-pins, rings or the like 18 for mounting the book leaves, all as best shown in Figs. 3 and 4, to provide a well known type of loose leaf book construction.

It will be evident that each of the panels 10, when normally in its closed position, with its back or top surface flush with the top surface 3 of the cabinet and with its book 8 hanging in the compartment 6, may be rotated until the edge 15 is stopped by the rear edge of the adjacent filler block 9. This disposes the panel at a slightly inclined position, as is best shown in Fig. 2, whereupon the covers of the book automatically fall open, and the leaves are exposed for turning on the top of the cabinet structure, as shown in Fig. 1. With the book cover and leaves open, and extended across adjacent panels, the book is supported in a stable manner and the panel is kept from accidentally rotating back to retract the book. However, when it is desired to restore the book to the compartment, it is necessary simply to close the book and turn the panel about the rod 11 so that the book rotates back into its compartment.

The space directly beneath the surface 3 may be used to store extra books or other articles, in much the same way as the cabinet space behind the lower rear wall 2 is used. One such stored book is shown at 19 in Fig. 2.

It has been found in actual practice that the structure thus described provides a very practical and useful cabinet for housing industrial reference books and making them readily available for opening, for removal, or for change of pages. The books are kept neatly and normally withdrawn and protected, and at the same time the cabinet provides a useful working surface in the manner of a table or desk. The abutment 14 operates to hold the surfaces of the elements 3 and 10 normally flush and level, and the panels 10 are not apt to be rotated accidentally because the normal pressure applied to them by a person standing behind the cabinet is pressure down

on their rear edges 15. To assist in preventing undesired rotation of the panels, they may be made slightly unbalanced, by locating the rod 11 a little off center, with more of the weight of the closed panel at the rear edge 15, as shown in Figs. 1 and 2. This tends to keep the closed panel flush with the surface 3.

The cabinet provided by the present invention will, it is believed, be found useful for purposes and in surroundings other than those which have been explained. Thus, with or without minor structural modifications, it may be used in libraries, business offices, telephone centers, etc., wherever there is need for giving protective housing to a frequently used reference book or set of books in an article of furniture from which the books cannot be removed but on which they may be readily opened and consulted.

The structure may be modified in numerous respects within the spirit of the invention and the scope of the appended claims, and all such modifications, to the extent that they incorporate the inventive principles as defined by the claims, are to be deemed within the scope and purview thereof.

I claim:

1. A cabinet having a normally flat top including a forward fixed portion having a rear abutment surface and including a movable rear panel having a forward abutment surface, a book-containing compartment below the panel, means mounting the panel for pivotal rotation about a horizontal axis, and a book secured to the panel, hanging in the compartment, and unbalancing the panel to urge said abutment surfaces into engagement, said panel being rotatable about the pivot means to bring the rear edge of the panel into engagement with the rear edge of the fixed portion of the top with the book projected above the level of the top.

2. A cabinet having a normally flat top including a forward fixed portion having a rear abutment surface and including a movable rear panel having a forward abutment surface, a book-containing compartment below the panel, means mounting the panel for rotation about a horizontal axis nearer the forward edge than the rear edge of the panel whereby the panel is unbalanced and said abutment surfaces are urged into engagement, and a book secured to the panel, normally depending in the compartment, but rotatable with the panel so as to be projected above the level of the cabinet top with the rear edge of the panel resting on the rear edge of the forward fixed portion of the cabinet top.

THOMAS H. LYONS.
